US0D1039507S

(12) **United States Design Patent** (10) **Patent No.:** **US D1,039,507 S**
Loussert (45) **Date of Patent:** **** Aug. 20, 2024**

(54) **ELECTRIC ACTUATOR**(71) Applicant: **Sonceboz Mechatronics Boncourt**,
Boncourt (CH)(72) Inventor: **Guillaume Loussert**, Boncourt (CH)(73) Assignee: **Sonceboz Mechatronics Boncourt**,
Boncourt (CH)(***) Term: **15 Years**(21) Appl. No.: **29/804,896**(22) Filed: **Aug. 23, 2021****Related U.S. Application Data**

(63) Continuation of application No. 35/507,940, filed on Feb. 20, 2019 (U.S. filing date under 35 U.S.C. 384), and having an international filing date of Feb. 20, 2019, now abandoned.

Primary Examiner — Nathaniel D. Buckner
(74) Attorney, Agent, or Firm — TraskBritt(57) **CLAIM**

The ornamental design for electric actuator, as shown and described.

DESCRIPTION

FIG. 1 is a bottom front right perspective view of an electric actuator showing my new design;

FIG. 2 is a top rear left perspective view thereof;

FIG. 3 is a bottom rear left perspective view thereof;

FIG. 4 is a bottom rear right perspective view thereof;

FIG. 5 is a top front perspective view thereof; and,

FIG. 6 is a top front right perspective view thereof.
